ROTARY INTAGLIO PRINTING PRESS

Arthur M. Wickwire, Jr., Mountain Lakes, N. J., assignor, by mesne assignments, to The Fred Goat Co., Inc., Brooklyn, N. Y., a corporation of New York

Application July 5, 1940, Serial No. 343,914

10 Claims. (Cl. 101—152)

This invention relates to printing presses and particularly to an improved rotary intaglio printing press and method of feeding a web therethrough.

In multicolor rotary intaglio printing, work is constantly being done to increase the speed of operation of the presses. One particularly important consideration in the design of any multicolor press involves the ratio of the length of "live web" (that portion of the web beyond the printing couple in which the printed surface does not contact any rollers) to the length of "dead web" (the web portion between the place where the printed surface first contacts a roller and the next printing couple); and it is desirable to maintain this ratio as high as possible. Another important consideration in connection with press design and higher press speeds, is the rate at which the ink will dry.

The recent development of presses in which inks containing very volatile solvents can be used has permitted higher press speeds. However, even though the ink may dry quickly, it is essential to provide a considerable length of live web between units of a multicolor press, in order that the web may be sufficiently dried to permit the proper application of a second color. Due to the usual arrangement of intaglio printing couples and the manner of inking an intaglio printing cylinder, the space beneath and between the printing couples has served no particularly useful purpose; and to provide the necessary length of live web for effective drying, the web has usually been led over some sort of elevated structure. Such structures, aside from requiring large amounts of space, have rendered the threading of the press somewhat difficult, and usually increased the length of dead web, with resulting problems in register.

Another important factor in connection with the general problem of gaining greater speed in intaglio printing is the adaptability of the press to rapid changes of the printing cylinders. Where highly volatile inks are employed and the major portion of the printing cylinder is enclosed in an ink housing, such changes are both difficult and time consuming.

I have discovered that when the web is arranged to be fed substantially vertically downwardly through a horizontally disposed printing couple, the remainder of the press may be designed so as to permit an increase length of live web between units with an accompanying utilization of the space below the printing couple and decrease in the length of dead web. Moreover,

such an arrangement is adapted for rapidly changing printing cylinders when desired.

In accordance with my invention, a substantially horizontally disposed printing couple is mounted in a pair of horizontal members of a printing unit frame. Rollers for directing the web into the printing couple are journaled in a suitable supporting structure arranged above the printing couple and the horizontal frame member. This particular supporting structure is movable with respect to the frame, and preferably is adapted to be swung or otherwise suitably moved to an inoperative position, thereby to permit ready access to the printing couple and easy removal of the printing cylinder. Rollers may be provided below the printing couple so that the printed web may be led, with the printed surface free from contact with any other surface, to the rollers in the movable supporting structure of the next adjacent printing unit, and thence to the printing couple thereof.

The above and other features and objects of my invention will become apparent upon consideration of the following description of a now preferred embodiment thereof, and the accompanying drawing, in which:

Fig. 1 is a side elevation view, somewhat diagrammatic, of a multicolor intaglio printing press embodying my invention;

Fig. 2 is a fragmentary plan view of one of the color units showing the details of the movable superstructure; and

Fig. 3 is a horizontal sectional view taken substantially along the line 3—3 of Fig. 1.

I have shown my invention, in the present instance, embodied in a rotary intaglio printing press of the general type disclosed in my copending application, Serial Number 217,139, filed July 2, 1938, and in the application of Irving Gurwick, Serial Number 168,715, filed October 13, 1937. It is to be understood, however, that the invention is not restricted in its use to such a machine, but may be used in rotary printing machines generally.

Referring now to the drawing, it will be observed that a web 10 of paper, cellulosic, textile, or other suitable material which is to be printed, is fed from a suitable source of supply (not shown) beneath a guide roller 12 and into a multicolor rotary intaglio printing press, which is designated as a whole by the reference numeral 14. The multicolor printing press may comprise a first color unit 16, a second color unit 18, and as many additional color units or other web treating devices as may be desired. Each color

unit is similar in construction to that disclosed in my copending application above referred to, and, as shown, comprises a main or lower supporting frame 20 and an upper frame 22 including a horizontal supporting member 24. Suitably supported in the horizontal supporting member 24 is a printing couple through which the web 10 is fed and printed. The printing couple may include a printing cylinder 26, such as an intaglio or engraved cylinder, and a resilient impression cylinder 28, which are arranged in a substantially horizontal position beside one another.

The upper frame portion 22 comprises a vertically disposed member extending above the horizontal member 24 and having a suitable projecting hub 30 provided adjacent the upper end thereof. Pivoted to the hub 30, at each side of the press, is an auxiliary movable supporting structure which comprises a substantially horizontally disposed member 32, having an integral downwardly extending foot 34 at the outer end thereof and arranged substantially at right angles thereto. It will be noted that the foot 34 is positioned above the impression cylinder 28, and is supported on a suitable shoulder 35 provided on the horizontal support 24.

As shown in Fig. 2, the horizontally disposed members 32, at each side of the press, form a support for the shafts of a main feed roll 36 and two auxiliary rollers 38 and 40. Feed roll 36 may be driven in any conventional manner, if desired. An idler gear 42 meshing with a gear 44 on the main feed roller 36 drives the roller 38 through a gear 46; and a second idler 48 meshing with the gear 46 and a gear 50 provided on the shaft of the roller 40 causes the latter to be rotated. As indicated in Fig. 1, the web 10 passes from roller 12 over driven roller 36, under roller 38, over roller 40 and then to the substantially horizontal printing couple 26, 28. From the printing couple, the web 10 passes downwardly over a guide roller 52 to a large roller 54 which is suitably mounted in bearing brackets 56 secured to the lower frame 20, and may be driven, if desired. At this point the web passes upwardly to the driven roller 36 of the next printing unit. Idler rollers 58 may be provided between the roller 54 and the next roller 36, if desired. It will be observed that from the printing cylinder 26 to the following roller 36, the printed surface of the web does not contact any roller. This provides, without any extra drying space, a maximum length of live web between printing units, so as to permit the ink to dry sufficiently before contacting a roller surface. It will also be noted that the length of dead web between the roller 36 and printing couple of the next printing unit is considerably shorter than in prior successful printing presses, thereby greatly reducing the possibility of the web to get out of register. These are considered important features of the present press arrangement.

To facilitate the drying of the web in its passage from the first printing couple 26, 28, to the roller 36 of the next printing unit, I have found it desirable to heat the roller 54 and so construct it and arrange it with respect to the first printing couple and the idler rollers 58 that a large area or length of contact for the web will be provided. As shown in Fig. 3, the roller 54 comprises a large hollow cylindrical shell or drum 60, about eighteen inches in diameter, having end walls 62 secured thereto in any convenient manner, such as by welding. Suitable

5 stub shafts or hubs 64 having axial passages 66 therein are rigidly mounted in the center of the end walls 62 for rotation in the brackets 56. The passage 66 in one of the hubs is closed by means of a plug 68 while the passage in the other hub is connected through a conventional rotary joint 70 with a fluid inlet pipe 72. An elongated siphon tube 74, which has its open end curved downwardly within the drum 60 to the lowermost part thereof, is disposed concentrically within the open passage 66 and connected through the rotary joint 70, to a fluid return pipe 76. With this construction, a suitable heating fluid, such as oil or water, may be circulated through the drum to heat the outside surface thereof to any desired elevated temperature for drying the ink applied by the first printing couple 26, 28. This manner of heating the roller 54 is conventional, and it will be understood that any desired heating means, such as electrical resistance elements, may be used in lieu thereof.

In Fig. 1, it will be noted that the heated roller 54 is of such a size and is so positioned that the web 10, in its passage to the next printing unit, is in contact with substantially 180° of the outside surface of said roller. When the web 10 consists of a material such as Cellophane, and when it is printed with a rather volatile rotogravure ink, and is moving at a speed of from 300 to 400 feet per minute in an apparatus of the form shown in Fig. 1, I have found that a web contact of from 160° to 180° (the angle A in Fig. 1) of drum surface and a drum temperature of between 110 F. and 150 F. assists in producing satisfactory drying of the first applied impression before the web contacts the roller 36 of the second printing unit. It will be understood that this manner of heating the freshly printed web causes drying to take place from the bottom of the ink film, rather than the exposed surface and thus effectively prevents skin drying of the film.

During the use of any printing press, changes in printing cylinders are often made. With the usual multi-color printing press where the printing couples are arranged in a substantially vertical plane instead of a horizontal plane, it is usually difficult to change printing cylinders. However, with my present arrangement, the changing of printing cylinders is greatly simplified, since the printing cylinder is not beneath the impression cylinder and the auxiliary supporting structure 32 is movable, as described above. I have provided additional mechanism for moving the auxiliary supporting structure to an inoperative position away from the printing couple, so that the members 32 constitute, in effect, a swinging superstructure.

60 As shown in the drawing, each of the members 32 has a gear segment 78, suitably mounted on the inner face thereof, and arranged substantially concentric with the pivot of the hub 30. The teeth of the gear segments 78 are adapted to mesh with the teeth of small gears 80 mounted on a shaft 82 which is journalled in the upper side frames 22 near the tops thereof. At one side of the press the shaft 82 may project through the adjacent frame member 22 and be provided with a suitable crank or handle 84. Thus, by rotating the crank 84 in a clockwise direction, the superstructure may be moved from operative position to the inoperative position indicated in dot and dash lines in Fig. 1. When in this position, it will be apparent that the

printing cylinder 26 may be readily removed from the bearings provided in the horizontal frame member 24.

It is to be understood that, if desired, a worm gear and pinion could be substituted for the gear segment construction described above; that various counterbalances may be employed for facilitating the raising of the superstructure; and that the shaft 82 may be rotated by means of a worm gear and pinion, or the superstructure raised directly by such means. Various other changes may be made in the construction and arrangement herein described, and certain features may be employed without others, without departing from the invention or sacrificing any of its advantages.

This application is a continuation-in-part of my copending application Serial No. 235,964, filed October 20, 1938.

What I claim is:

1. In a printing press, the combination of side frames; a substantially horizontally disposed printing couple supported by said side frames; and a movable superstructure pivotally secured to said side frames above said printing couple and carrying means for guiding a web to said printing couple.

2. In a printing press, the combination of side frames; a substantially horizontally disposed printing couple supported by said side frames; and a movable superstructure pivotally secured to said side frames above said printing couple, said movable superstructure having a plurality of rollers journalled therein for guiding a web to a position above said printing couple.

3. In a printing press, the combination of side frames; a substantially horizontally disposed printing couple supported by said side frames; a movable superstructure pivotally secured to said side frames above said printing couple and carrying means for guiding a web to said printing couple; and means for moving said superstructure to an inoperative position away from said printing couple so as to permit ready access thereto.

4. In a multicolor printing press, the combination of side frames; a plurality of substantially horizontally disposed printing couples journalled in said side frames; and a plurality of movable superstructures pivotally secured to said side frames, one of said movable superstructures being arranged above each of said printing couples for guiding a web thereto.

5. A rotary printing press, comprising a pair of side frames each including a horizontal member and a vertical member extending above said horizontal member; a printing cylinder journalled in said horizontal members; and a movable superstructure pivotally secured to said vertical members and carrying means for guiding a web to said printing cylinder.

6. A rotary printing press, comprising a pair

of side frames each including a horizontal member and a vertical member extending above said horizontal member; a printing cylinder journalled in said horizontal members; and means for guiding a web to said printing cylinder, said means being carried by a movable superstructure pivotally secured to said vertical members and having feet contacting said horizontal members when it is in operative position.

10. 7. A rotary printing press, comprising a pair of side frames each including a horizontal member and a vertical member extending above said horizontal member; a printing cylinder journalled in said horizontal members; a movable superstructure pivotally secured to said vertical members and having feet contacting said horizontal members when it is in operative position said superstructure carrying means for guiding a web to said printing cylinder; and means for moving said superstructure to an inoperative position away from said printing cylinder.

8. A rotary printing press, comprising a pair of side frames each including a horizontal member and a vertical member extending above said horizontal member; a printing cylinder journalled in said horizontal members; a movable superstructure pivotally secured to said vertical members and having feet contacting said horizontal members when it is in operative position said superstructure carrying means for guiding a web to said printing cylinder; and means for moving said superstructure to an inoperative position away from said printing cylinder, said last mentioned means including a gear segment secured to the superstructure and a gear adapted to mesh therewith.

9. A rotary printing press, comprising a pair of side frames each having an integral projecting hub near the top thereof; a substantially horizontally disposed printing couple supported by said side frames; a movable superstructure pivotally secured to said hubs and disposed above said printing couple said superstructure carrying means for guiding a web to said printing couple; and means for moving said superstructure to an inoperative position away from said printing couple.

10. In a multicolor printing press, the combination of side frames; first and second substantially horizontally disposed printing couples journalled in said side frames; a movable superstructure pivotally mounted in said side frames and disposed above said second printing couple, said superstructure carrying means for guiding a web to said second printing couple; and means for guiding a web downwardly from said first printing couple and then upwardly directly to the guiding means carried by said superstructure, the freshly printed surface of the web being free from contact with any surface between said first printing couple and said superstructure.
